UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

STEAM BOILER

Application filed June 21, 1920. Serial No. 390,358.

My invention particularly relates to a steam boiler which may be used either in waste heat work or for direct firing, and in which a high rate of heat transfer is obtained.

My invention will best be understood by reference to the accompanying drawings, in which like reference characters indicate like parts, and in which Figure 1 is a longitudinal sectional view of a steam boiler embodying my invention adapted for waste heat work; Fig. 2 is a vertical transverse section through Fig. 1; Fig. 3 is a longitudinal section through a steam boiler embodying my invention adapted for direct firing; Fig. 4 illustrates diagrammatically the arrangement of the tubes of the upper bank of the supplemental circulatory system of the arrangement shown in Fig. 3; Fig. 5 is a view similar to Fig. 4 illustrating the arrangement of the tubes of the lower bank of the supplemental system of the arrangement shown in Fig. 3; Fig. 6 is a sectional view taken on the line 6—6 of Fig. 3; Fig. 7 is a sectional plan view taken on the line 7—7 of Fig. 3; Fig. 7^a is a detail sectional view illustrating the lower ends of the economizer tubes; Fig. 8 is a longitudinal sectional view of another form of boiler embodying my invention adapted for waste heat work; Fig. 9 is a section taken through Fig. 8; Fig. 10 is an end view of the boiler shown in Fig. 8; Fig. 11 is a longitudinal sectional view of a modified form of steam boiler for waste heat work embodying my invention; Fig. 12 is a sectional elevation taken on the line 12—12 of Fig. 11, and Fig. 13 is an end view of the transverse diaphragm or partition of the lower mud drum.

Referring, now, to the drawings, and first to Figs. 1 and 2, 10 is an upper steam and water drum, and 11 and 12 two lower aligned mud drums connected to the steam and water drum by banks of boiler tubes 13 and economizer tubes 14, respectively, the tubes being arranged in staggered rows longitudinally of the boiler and in straight rows transversely thereof, the tubes being bent at their ends where they enter the drums. The tubes are arranged, longitudinally of the drums, in groups, preferably of two, which are spaced apart to afford access for removal and re-

newal of the tubes and for adjustment of the scrapers, when used, which are shown in Figs. 8, 9 and 10, but which may be used on any of the forms of boilers illustrated, including the one under consideration. Ordinarily, however, the tubes would be cleaned by rotary soot blowing elements 15, the rotating means and intake for which are indicated at 16. The waste heat gases—such, for example, as may be obtained in the manufacture of zinc, and carrying zinc oxide dust—are conducted to the boiler by a flue 18, which directs the gases over the tubes 13 and 14. Some of the tubes, preferably near the tubes against which the gases first impinge, may be superheater tubes, as in Fig. 8. From the boiler tubes 13 the gases pass over the economizer tubes 14, the gases being carried from the boiler by the outlet flue 19, the side walls 20 of the setting confining the gases to the tubes during their passage thereover. The feed water inlet 21 is connected to the mud drum 12 of the economizer, which, in Figs. 1 and 2, is shown separate from the mud drum 11. By placing the dry pipe and steam outlet 17 at the rear end, with respect to the flow of gases, of the steam and water drum, steam of a maximum degree of dryness is obtained, as the water in the drum is in the most quiescent state and at the lowermost level at this point. Beneath the lower drums 11 and 12 are arranged pockets having hopper-shaped tops, which are provided for the reception of zinc oxide or other deposit which may collect on the tubes and which may be removed by the scrapers, or the steam soot blowing elements, or in any desired manner.

In Figs. 3, 4, 5, 6 and 7, I have illustrated my invention embodied in a steam boiler of the direct-fired type. The feed water inlet 21^a is connected to the mud drum 12^a of the economizer. The mud drum 12^a may be separate from the mud drum 11^a of the boiler, as in Figs. 1 and 11, or it may be a continuation of the mud drum 11 and separated therefrom by a partition 22, as shown in Figs. 3 and 7. In the form here shown, the mud drum 12^a is formed as a continuation of the mud drum 11^a, and is separated therefrom by a partition 22, as shown in Figs. 3 and 7.

The drum 10 is connected to the drums 11^a and 12^a by banks of tubes 13^a and 14^a, respectively. The partition 22 may be provided with a manhole or manholes 23 or other openings, as shown in Fig. 13. The opening or openings in the partition 22 will ordinarily be kept closed when the boiler is operated. In case the opening or openings in the partition 22 are left open the economizer section 10 will be connected to the general circulation of the boiler and the economizer tubes will become boiler tubes. The use of the partition 22 with the opening or openings therein provides a means of connecting the economizer with the general circulation of the boiler, thereby converting the economizer section to a boiler section. In some instances feed water will cause corrosion in economizer elements and not in the boiler. Should this be the case, the feature of converting the economizer tubes to boiler tubes is a most useful one, as the economizer can be converted and made part of the boiler and the corrosion thereby overcome until such a time that the feed water can be treated so as to make it suitable for use in an economizer. The manhole openings 23 in the partition 22 serve a further useful purpose in providing access from the economizer drum to the boiler drum or vice versa. In some instances, it is desirable to dispense with a manhole at the furnace or hottest end of the boiler mud drum 11^a, and when this is done, the boiler mud drum may be entered through the manhole openings 23. By providing the partition with a plurality of openings having removable covers the communication between the two chambers may be varied according to the number of covers removed.

Ferrules 24 or other forms of retarders may be placed in the lowermost ends of the economizer tubes in any of the economizers, as shown in Fig. 7^a, in order to divide the water more evenly between the different tubes than it would be divided without the use of such retarding means. The ferrules or retarders serve to prevent a general circulation being started up within the economizer that would carry some of the hot water from the upper steam and water drum downward to the lower economizer drum.

The steam boiler is provided with a stoker 25, which is here illustrated as of the under-feed type, a combustion chamber 26 being formed between the front wall 27 and the rear wall 28, the latter preferably being provided with openings 29 which afford access to the dumping plates of the stoker and to the fuel bed, the rear wall preferably being inclined, as indicated. In the form of my invention here shown, a supplemental circulatory system is interposed between the furnace and the boiler tubes, comprising a lower bank of tubes 30 and an upper bank 65 of tubes 31 connected at their front ends to

a common chamber, which is here shown as formed by a drum 32 arranged above and in front of the front wall 27 of the furnace, the tubes 30 and 31 being arranged at an angle, as shown, and forming a secondary combustion chamber 33 for the furnace gases. A roof baffle 34 of any desired length may be used above and at the rear of the lower bank of tubes 30, and extends forwardly from the rear furnace wall 28, as shown, and directs the gases forwardly to the secondary combustion chamber. Each bank of tubes 30 and 31 preferably comprise two rows in order that there may be enough cooling effect to prevent overheating of the furnace walls, whereas they will not cool the gases which enter the secondary combustion chamber below a temperature suitable for securing complete combustion in the secondary combustion chamber. The tubes of the lower bank are arranged one above the other as indicated in Fig. 5, while those of the upper bank are staggered as indicated in Fig. 4. The other ends of the banks of tubes 30 and 31 are connected to drums 35 and 36, respectively, the drum 35 being disposed at the rear of the furnace wall 28, as shown. A dry pipe 17 is located above the tubes of the economizer as in Figs. 1 and 2. The drum 35 is connected to the mud drum 11^a by water tubes 37, while the upper drum 36 is connected to the steam and water drum 10 by water tubes 38. The drum 36 is also connected to the steam and water drum 10 by steam pipes 39. The furnace, which is of the same width, or substantially the same width, as the secondary combustion chamber, is wider than the portion of the flue in which the tubes are arranged, as best shown in Fig. 7. The side walls 40, forming the flue inlet, in which the tubes are disposed, are flared outwardly, as at 41 (see Fig. 7), and the tubes are arranged substantially to fill the flue transversely thereof so that the boiler tubes 13^a against which the gases from the furnace first impinge are disposed in a wider space and are further spaced apart than are the remaining tubes. In an ordinary boiler, where the tube spacing between the tubes and the tube lengths are uniform throughout the length of the boiler, the velocity of the gases is much lower on passing over the last tubes than it is on passing over the first tubes, on account of the increase in density of the gases as they decrease in temperature. In accordance with my invention, the flue and boiler tubes are so arranged that the area for the passage of the gases at the successive rows of tubes in the first portion of the boiler decreases by decreasing the width of the flue and of the spaces between the tubes, and in this manner I obtain a gradually decreasing flow area so as to maintain a velocity of the gases over the tube surface, which leads to the best results. By making the furnace and 130

the supplemental circulatory system wider than the major portion of the flue in which the tubes 13^a and 14^a are located, a furnace and a secondary combustion chamber of ample proportions for the thorough combustion of the gases are provided.

Inclining the rear wall 28 in the manner indicated, when combined with the roof baffle 34, is particularly adaptable to an underfeed stoker where excess air, under certain conditions of operation, passes from the rear part of the stoker mechanism, and through the dumping plates, and is projected rearwardly into the furnace. The form of the tuyères of the stoker, which admit the compressed air, causes the air to be projected rearwardly, and when the rear portion of the fire becomes thin, or when a portion of the fire is broken through by the action of the blast, the construction of the tuyères is such as to project the air and gases rearwardly. It can readily be seen that where a stoker produces such an action, the form of furnace is particularly adapted to give increased efficiency, particularly in combination with a secondary combustion chamber of the character described and with a boiler of the type here illustrated.

In Figs. 8, 9 and 10 I have shown my invention embodied in a modified form of waste heat boiler. A single mud drum 42 is connected to the steam and water drum 10 by tubes 43, the waste heat gases being admitted to the boiler through the inlet flue 44, and, after passing over the tubes, leave by the outlet flue 45. A plurality of spaced baffle plates 431 extend upwardly from the bottom of the space beneath the mud drum 42 between the lower ends of the tubes 43 sufficiently to prevent the gases from being short-circuited around the tubes through the space beneath the tubes. These baffles, of course, closely surround the mud drum 42. The steam is collected by a dry pipe 46 disposed at the rear end of the boiler, from which the steam passes to the outlet pipe 47, which is connected to the lower header 48 of a superheater, from which the steam passes through the superheater tubes 49 to the upper header 50, the superheater tubes in this form being disposed between the boiler tubes, and the headers being arranged transversely of the drums and supported in the setting, as shown. The header 50 is provided with a steam outlet 51, as best shown in Fig. 9. I have here illustrated scrapers 52 for removing zinc oxide or other deposit from the tubes, although, as previously stated, the scrapers may be used in the other forms of boilers illustrated. The scrapers are mounted on cross-heads 53, which may be operated by chains 54 passing over pulleys 55, one set of scrapers being balanced against the other in a known manner, and the chain for the set of scrapers at one end being attached to counterweights 56.

In the boilers shown in Figs. 1 to 10, in-

clusive, the gases make a single pass transversely of the boiler tubes, thereby eliminating the draft resistance due to changes in the direction of flow of the gases which occur in boilers provided with baffles. The tubes are so proportioned and spaced that the flow area over the tubes, between and around the tubes, in combination with the staggered arrangement of the tubes, gives a high rate of heat transfer from the hot gases to the tubes. A maximum heat transfer is thereby secured, with a minimum draft resistance, and the arrangement is particularly adaptable for securing high efficiencies.

In Figs. 11 and 12 I have illustrated another form of steam boiler adapted for waste heat work, and in which parts arranged similar to those of the previously described figures are similarly numbered, but where baffles are used to give a longitudinal flow of the gases along the tubes. The gases enter the boiler by two flues 57 controlled by gates 58. In this form of my invention, the boiler tubes and economizer tubes are bent outwardly away from the center line passing through the two drums, near one end of the tubes (as here shown, the lower ends of the tubes), so that the two banks of tubes on either side of the center line are spaced apart in the manner shown in Fig. 12, the direction of tubes from the bent portions being inclined to the center line. In the form here shown, the boiler tubes are separated into definite sections 13^b, 13^c and 13^d by baffles or walls 59 and 60 extending transversely of the drums, the baffle or baffles 59 extending upwardly from the foundation wall 61, while the baffle or baffles 60 are suspended beneath the steam and water drum 10. A wall 62 is disposed between the boiler tubes 13^d and the economizer tubes 14^a. Alternate baffles or walls 59 and 62 are provided with central openings 63 and 64, respectively, at the top, while the alternate baffle or baffles 60 are provided at their lower ends with two openings 65 on either side of the center line, these openings being approximately in alignment with the flues 57. The gases entering through the flues 57, therefore, are directed against the bent portions of the two banks of tubes, and then flow longitudinally of the tubes between the baffle 59 and the end wall of the setting, passing through the central opening 63 of the baffle 59. The gases then flow along the tubes of the second bank, and through the two openings 65 of the baffle 60, and, in a similar manner, over the remaining tubes, until they pass to the outlet 66, from which the gases are drawn to the stack by a fan 67. The gases thus pass from the inlet flues to the bent ends of the tubes where they are widened, and thence longitudinally of the tubes to the single opening 63 in the baffle 59, and so on through the boiler, the gases passing serially over the banks of tubes delimited by the baffles, and, in general, flowing longitudi-

nally along the various banks of tubes. In the arrangement shown in Fig. 11, the steam and water drum is extended toward the rear and the dry pipe made to come in the part of 5 the steam and water drum so extended. By employing this construction, the steam is taken from above water which is in a more quiescent state than should it be taken at a nearer point to the front end of the drum, 10 and the advantage of obtaining steam of the maximum dryness is thereby secured.

What I claim and desire to secure by Letters Patent of the United States is:

1. In a steam boiler, an upper steam and 15 water drum, two substantially aligned lower water chambers, a feed-water connection to first of said water chambers, economizer tubes connecting said first feed-water chamber to the upper steam and water drum, boiler tubes connecting the other water chamber to the steam and water drum, a furnace, and a supplemental circulatory system interposed between said furnace and said tubes, and comprising two banks of tubes connected at one 20 end to a common chamber, the other ends of said two banks of tubes being connected to said steam and water drum and to the second-mentioned water chamber, said tubes forming a secondary combustion chamber.
2. In a steam boiler, an upper steam and water drum, a lower mud drum substantially parallel thereto, and tubes having their ends entering and connected to said drums, a flue in which the tubes are located for directing 35 the gases over said tubes in a single, unobstructed pass, the tubes being arranged in rows transversely of the boiler, the portion of the flue enclosing the boiler tubes against which the gases first impinge being wider in a horizontal plane than the remainder of the flue, and the tubes therein being further spaced apart than are the tubes in the remainder of the flue, the tubes substantially filling the portion of the flue in which they 40 are located.
3. In a steam boiler, an unobstructed upper steam and water drum, two lower mud drums, the one formed as a continuation of the other and separated by a transverse partition provided with an opening, a removable cover for closing said opening, tubes connecting the respective drums to the steam and water drum, the gases flowing over said tubes in a single pass, and means for introducing 45 feed water to one of said mud drums.
4. In a steam boiler, an upper steam and water drum, a lower mud drum provided with a partition arranged transversely of the drum forming two chambers therein, 50 banks of water tubes and of economizer tubes connecting said upper steam and water drum to the respective chambers of said lower drum, the gases flowing over said tubes in a single pass, means for introducing feed water to one of said drums, said partition being 55

provided with an opening, and means for closing said opening, whereby the economizer tubes may be operated separately from or as a part of the general boiler circulation at will.

5. In a steam boiler, a steam and water drum set parallel to the general direction of the flow of the furnace gases over the boiler tubes, boiler tubes connected to one end of said drum, an economizer section comprising tubes connected to the other end of said steam and water drum and through which the water flows to said drum the gases flowing in succession over said boiler tubes and then over said economizer tubes, a steam outlet connected to said drum near the rear end thereof 70 with respect to the flow of gases, and a dry pipe connected to said steam outlet and extending towards the rear end of the drum 75 with respect to the flow of gases.

6. In an economizer, upper and lower 80 chambers, means for introducing feed water to the lower chamber, a bank of economizer tubes connecting the upper and lower chambers, said tubes being provided with restrictions for preventing a reverse circulation in 85 any of said tubes.

7. In an economizer, upper and lower 90 chambers, means for introducing feed water to the lower chamber, a bank of economizer tubes connecting the upper and lower chambers, said tubes being provided with ferrules for preventing a reverse circulation in 95 any of said tubes.

8. In an economizer, upper and lower 100 chambers, means for introducing feed water to the lower chamber, a bank of economizer tubes connecting the upper and lower chambers, said tubes being provided at their lower ends with ferrules for preventing a reverse 105 circulation in any of said tubes.

9. In a steam boiler, an upper steam and water drum, two lower water chambers, banks of economizer and boiler tubes connecting the respective water chambers to said upper steam and water drum, means for introducing feed water to one of said chambers, the tubes connected to the last-named chamber being provided with ferrules whereby a reverse circulation in any of the economizer tubes is prevented.

10. In a steam boiler, an upper steam and water drum, two lower substantially aligned water chambers, banks of economizer and boiler tubes connecting the respective lower water chambers to said upper steam and water drum, means for introducing feed water to the water chamber to which the economizer tubes are connected, said economizer tubes being provided with ferrules whereby a reverse circulation in any of the 115 economizer tubes is prevented.

11. In a steam boiler, upper and lower water chambers connected by water tubes, a flue in which the tubes are located for directing the gases over said tubes longitudinally 120

of the boiler in a single pass, a space being provided below the water tubes, and a plurality of baffles extending upwardly transversely of the flow of gases and across said 5 space to prevent substantial short circuiting of the gases through said space.

12. In a steam boiler, upper and lower water chambers connected by water tubes, a flue in which the tubes are located for directing the gases over said tubes longitudinally of the boiler in a single pass, a space being provided below the water tubes, and a plurality of baffles extending upwardly transversely of the flow of gases and across said 10 space, the upper ends of said baffles extending between the water tubes to prevent substantial short circuiting of the gases through said space.

13. In a steam boiler, an upper steam and water drum, two substantially aligned lower water chambers, a feed water connection to one of said water chambers, economizer tubes connecting the feed water chamber to the upper steam and water drum, boiler tubes 25 connecting the other water chamber to the steam and water drum, a furnace, a supplemental circulatory system interposed between said furnace and said tubes and comprising two banks of tubes connected at one end to a common chamber, the other ends of said two banks of tubes being connected to said steam and water drum and to the second-mentioned water chamber, said tubes forming a secondary combustion chamber, and a 30 dry pipe for the steam located in the upper portion of the steam and water drum above the economizer tubes.

14. In a steam boiler, an upper steam and water drum, a lower mud drum, tubes connecting said steam and water drum to said mud drum, a furnace, and a supplemental circulatory system interposed between said furnace and said tubes, and comprising two 45 banks of tubes connected at one end to a common chamber, the other ends of the tubes being connected to the lower and upper drums, respectively, said tubes forming a secondary combustion chamber, and the lower bank of tubes comprising two rows arranged one 50 above the other.

15. In a steam boiler, an upper steam and water drum, a lower mud drum, tubes connecting said steam and water drum to said mud drum, a furnace, and a supplemental 55 circulatory system interposed between said furnace and said tubes, and comprising two banks of tubes connected at one end to a common chamber, the other ends of the tubes being connected to the lower and upper 60 drums, respectively, said tubes forming a secondary combustion chamber, and the lower bank of tubes comprising two rows arranged one above the other, the number and arrangement of the tubes in said circulatory system 65 being such that they exert sufficient cooling

effect upon the gases to prevent overheating of the furnace walls and at the same time permit the gases to enter the secondary combustion chamber formed between the tubes of said circulatory system at a temperature sufficiently high for securing complete combustion of the gases in said secondary combustion chamber.

16. In a steam boiler, an upper steam and water drum, a lower mud drum, tubes connecting said steam and water drum and said mud drum, a furnace, a supplemental circulatory system comprising an upper and a lower bank of tubes located in advance of said first mentioned tubes with respect to the flow of gases and connected at one end to a common water chamber and extending in different directions to form a secondary combustion chamber, the other ends of the tubes of said banks being connected at their other ends to said steam and water drum and to said mud drum, respectively, the gases flowing from said furnace over the tubes of one of said banks into said secondary combustion chamber and thence over the tubes connecting said steam and water drum to said mud drum.

17. In a steam boiler, an upper steam and water drum, a lower mud drum, tubes connecting said steam and water drum and said mud drum, a furnace, a supplemental circulatory system comprising an upper and a lower bank of tubes located in advance of said first mentioned tubes with respect to the flow of gases and connected at one end to a common water chamber and extending in different directions to form a secondary combustion chamber, the other ends of the tubes of said banks being connected at their other ends to said steam and water drum and to said mud drum, respectively, the gases flowing from said furnace over the tubes of one of said banks into said secondary combustion chamber and thence over the tubes connecting said steam and water drum to said mud drum, and a roof baffle disposed above the lower bank of tubes and extending forwardly from the furnace wall for directing the gases to said secondary combustion chamber.

18. In a steam boiler, an upper steam and water drum, a lower mud drum, tubes connecting said steam and water drum and said mud drum, a furnace, a supplemental circulatory system comprising an upper and a lower bank of tubes located in advance of said first mentioned tubes with respect to the flow of gases and connected at one end to a common water chamber and extending in different directions to form a secondary combustion chamber, the other ends of the tubes of said banks being connected at their other ends to said steam and water drum and to said mud drum, respectively, the gases flowing from said furnace over the tubes of one of said banks into said secondary combustion

chamber and thence over the tubes connecting said steam and water drum to said mud drum, the tubes of said lower bank through which the gases flow being arranged one above the other.

19. In a steam boiler, an upper steam and water drum, a lower mud drum, tubes connecting said steam and water drum and said mud drum, a furnace, a supplemental circulatory system comprising an upper and a lower bank of tubes located in advance of said first mentioned tubes with respect to the flow of gases and connected at one end to a common water chamber and extending in different directions to form a secondary combustion chamber, the other ends of the tubes of said banks being connected at their other ends to said steam and water drum and to said mud drum, respectively, the gases flowing from said furnace over the tubes of one of said banks into said secondary combustion chamber and thence over the tubes connecting said steam and water drum to said mud drum, and a roof baffle disposed above the lower bank of tubes and extending forwardly from the furnace wall for directing the gases to said secondary combustion chamber, the tubes of said lower bank being exposed for substantially their entire length of the radiant heat of the furnace.
20. In a steam boiler, an upper steam and water drum, a lower mud drum, tubes connecting said steam and water drum and said mud drum, a supplemental circulatory system comprising an upper and a lower bank of tubes located in advance of said first mentioned tubes with respect to the flow of gases and connected at one end to a common water chamber and extending in different directions to form a secondary combustion chamber, other drums to which the opposite ends of the tubes of said banks are connected, and connections between said last mentioned drums and the steam and water drum and mud drum, respectively.

DAVID S. JACOBUS.
